UNITED STATES PATENT OFFICE.

FRED C. BELL, OF COEUR D'ALENE, IDAHO, ASSIGNOR, BY DIRECT AND MESNE ASSIGNMENTS, TO N. S. PAUL, OF SAME PLACE.

ADJUSTABLE HANGER FOR INCANDESCENT LIGHTS.

SPECIFICATION forming part of Letters Patent No. 601,930, dated April 5, 1898.

Application filed March 26, 1895. Serial No. 543,215. (No model.)

To all whom it may concern:

Be it known that I, FRED C. BELL, a citizen of the United States, residing at Coeur d'Alene, in the county of Kootenai and State of Idaho, have invented a new and useful Improvement in Adjustable Hangers for Incandescent Lights, which improvement is fully set forth in the following specification and accompanying drawings.

10 My invention relates to that class of hangers for incandescent electric and other lights in which the light or lamp is suspended from a cord which is wound in opposite directions upon a vertically-movable spring-actuated drum, so that the light may be readily elevated and lowered or adjusted vertically to any position desired.

15 The invention consists in the novel construction and combination of parts hereinabove fully described and claimed.

20 In the accompanying drawings, Figure 1 is a side elevation of an electric-light hanger constructed in accordance with my invention, partly broken away. Fig. 2 is a side view of 25 the same. Fig. 3 is a vertical sectional view. Fig. 4 is a detail perspective view of the notched disk and holding dogs or pawls. Fig. 5 is a similar view of one of the rollers with which the winding-cord engages.

30 In the said drawings the reference-letter A designates a drum comprising the circular end disks 1¹ and the rim 2, the disks being of greater diameter than the rim, so as to project beyond the same and form guides for 35 the suspending-cord hereinafter described. Passing loosely through these disks is a spindle 3, provided at one end with a hub 4, securely fixed thereto, and secured to this hub are two oppositely-extending radial arms 5 and 6, consisting of metal wires or rods, the outer ends bent into a quadrangular loop 4¹, which are at an angle to the said arms, to one 40 of the arms of which is journaled a grooved roller 8, which are in different vertical planes 45 from the arms.

The numeral 9 designates a disk or collar fixed to the spindle and provided at its periphery with two notches 9¹, diametrically opposite each other, with which are adapted 50 to engage two dogs or pawls 10, which move with the drum when it is rotated on the spin-

55 dle in elevating and lowering the light. The numeral 12 designates pins or stops secured to said plate which act as stops for the dogs or pawls.

55 The numeral 13 designates a coiled spring the inner end of which is secured to the spindle 3, while the outer end is attached to a stud 14, secured to the rim of the drum. The numeral 15 designates a circular shield fixed to 60 the said spindle and located within the drum. This shield is provided with a flaring flange at its edge which projects over the pawls and notched disk to prevent interference therewith by the coiled spring. 65

Secured to the rim of the drum, in the outside thereof, is a hook 16, with which engages the suspending-cord 17, which is wound around the drum in opposite directions, and a lamp or light secured to its lower end and its upper end secured to a ceiling or other place or object. 70

75 The operation is as follows: The suspending-cord is engaged intermediate its ends with the hook on the drum and wound around the latter a number of times and the ends passed through the loops in the ends of the arms 5 and 6 and bearing against the inner sides of the rollers 8, as seen in Fig. 1. The spindle-hub 4 is then held and the drum given a few 80 turns in the direction of the arrow to partially wind the spring, one of the dogs or pawls 10 engaging with the upper notch in the disk 9 to prevent backward or reverse movement of the drum by the tension of the 85 spring. The upper end of the cord is now secured to a ceiling or other place or object, and, the drum being prevented from rotating, the light or lamp will be held against downward movement. To lower the lamp, it is 90 given a downward pull, which will throw the arms 5 and 6 out of perpendicular by reason of the cord bearing against opposite sides of the rollers, which are in different vertical planes from said arms. This will cause the 95 spindle to be rotated to the right, which will throw the pawl or dog out of engagement with the notch of the disk, allowing the rope to unwind from the drum, which will be rotated in the direction of the arrow. So long as the 100 pull upon the lower end of the cord is sufficient to keep the arms out of perpendicular,

as set forth, the dogs or pawls will ride past the notches without engaging therewith; but when the lamp or light is released the arms 5 and 6 will return to normal position, allowing one of the dogs or pawls to engage with one of the notches of the disk and hold the drum in its adjusted position. To elevate the lamp or light, it is pulled down to release the dog from the notch in the disk, as before stated, and then by allowing the cord to slacken a little without releasing the hold on the lamp or light the latter will be elevated.

What I claim is—

1. The combination with the rotatable drum, 15 having a hook on its periphery, and the pivoted dogs and the pins on the inside of one of the heads thereof, of the spindle the notched disk fixed thereto, the hub secured to said spindle, the radial arms secured to said hub 20 having quadrangular loops at the outer ends, the rollers journaled to said loops and lying in different planes from said arms, and the rope engaging with said hook and wound

around the drum and its ends passed through said loops and bearing against said rollers, 25 substantially as described.

2. The combination with the rotatable drum having a hook on its periphery, and the pivoted dogs and pins on the inside of one of the heads thereof, of the spindle the flaring shield 30 secured thereto, the notched disk secured to said spindle with which the said dogs engage, the hub secured to said spindle, the radial arms having quadrangular loops at the outer ends, the rollers journaled thereto in different planes and the cord connected with said hook and wound around the drum and its ends passed through said loops and bearing against said rollers, substantially as described. 35

In testimony that I claim the foregoing I 40 have hereunto set my hand, this 8th day of March, 1895, in the presence of witnesses.

FRED C. BELL.
